Poitevent, Carrere & Denegre, LLP

(57) **CLAIM**

The ornamental design for a pedicure spa base, as shown and
described.

DESCRIPTION

FIG. 1 is a front, side perspective view of the pedicure spa
base showing the location of the spa chair and spa basin.

FIG. 2 is a front, side perspective view of the pedicure spa
base.

FIG. 3 is a rear side elevation view of the pedicure spa base.

FIG. 4 is a right side elevation view of the pedicure spa base.

FIG. 5 is a front elevation view of the pedicure spa base.

FIG. 6 is a left side elevation view of the pedicure spa base.

FIG. 7 is a rear elevation view of the pedicure spa base; and,
FIG. 8 is a top plan view of the pedicure spa base.

The broken lines in the drawings, particularly those depicting
a massage chair and basin shown in FIG. 1, are for illustrative
purposes only and form no part of the claimed design.

1 Claim, 7 Drawing Sheets
